DOUBLE-ACTING PIPE-WRENCH.

1,150,663.

Specification of Letters Patent. Patented Aug. 17, 1915.

Application filed March 6, 1915. Serial No. 12,544.

To all whom it may concern:

Be it known that I, ROBERT J. COSSEBOOM, a citizen of the United States, and a resident of Buena Vista, in the county of Chaffee and 5 State of Colorado, have invented a certain new and useful Improvement in Double-Acting Pipe-Wrenches, of which the following is a specification.

This invention relates to an improvement 10 in wrenches, and more particularly to that class of wrenches in which a flexible chain is utilized in gripping the work.

One of the principal objects of the invention is to provide an improved wrench of 15 the type set out having a claw or jaw shiftable longitudinally of the wrench into engagement with the work to exert a binding force thereagainst in a direction opposed to that of the chain, and in such manner 20 that the wrench may be manipulated in either direction without danger of slipping.

Another object is to provide a wrench of 25 the class described having a longitudinally shiftable claw and having a lever adapted simultaneously and by manipulation in a single direction, to operate both the chain and claw in opposite directions, whereby to exert opposed tensions upon the work and thereby positively lock the wrench thereon.

30 A further object is to provide such a wrench as I have disclosed having few parts readily detachable from each other for repair or renewal.

Still another object is to provide a device 35 of the class described which will be extremely simple, durable, efficient in operation and inexpensive to manufacture.

With these and other objects in view which will become apparent as the description 40 proceeds, the invention resides in the construction, combination, and arrangement of parts hereinafter more fully described and claimed, and illustrated in the accompanying drawings in which like characters 45 of reference indicate like parts throughout the several figures of which—

Figure 1 represents a view in side elevation of a wrench constructed according to my invention, the parts being shown in the

position taken just prior to the final binding 50 movement of the lever; Fig. 2 represents a view in side elevation, with one of the walls of the handle removed, showing the wrench in final locked position upon a pipe section; Fig. 3 represents a view in section taken 55 vertically and transversely through the handle on the plane indicated by the line 3—3 of Fig. 2; Fig. 4 represents a view in perspective of the claw and its shank removed from the wrench; Fig. 5 represents a view 60 in section taken vertically and transversely through the wrench on the plane indicated by the line 5—5 of Fig. 2.

In carrying out my invention, I provide a wrench handle indicated generally at 5 of 65 substantially a semi-tubular or U-shape in cross-section. The outer end of handle 5 is reduced as at 6 to provide a hand hold. The inner end of the handle is flared in opposite directions to provide pairs of spaced ears 70 indicated at 7 and 8 respectively. Ears 8 are provided on the floor or closed side of handle 5, and are defined by an opening at 9 cut in the floor in the inner end of the handle. Through this opening extends one terminal link of a chain 10, said link being 75 pivotally connected between the side walls of the handle by means of a screw or other suitable fastening element 11.

Between the ears 7 which occur on the 80 open side of the handle is pivoted at its inner end, a lever 12. A screw or other suitable element 13 is utilized in detachably pivoting the lever to the handle. The outer end of the handle 14 is offset whereby to 85 engage within the channel of the reduced end 6 of the handle when said lever and handle are in closed position as indicated in Fig. 2. Lever 12 is provided on its outer surface a short distance from pivot point 13, 90 with a lug 15 having a recessed side 16 adapted to engage one of the pintles of the chain in the manner indicated in Fig. 1 when the lever is in outwardly swung position with regard to the handle, so that 95 when the lever is swung against the handle, the chain will be tightened about the work and exert a tension thereagainst in the di-

rection of the handle. The lug or spur 15 projects as will be seen toward the outer end of lever 14.

Slidably disposed between the side walls 5 of the handle at the inner ends thereof, is a shank 17 provided at spaced intervals with a plurality of elongated openings or slots 18. The shank is shiftable longitudinally of the handle and is maintained in position 10 in the handle by means of a plurality of removable screws or other fastening elements 19. These screws limit the longitudinal shifting movement of the shank. At its outer end the shank is provided with a jaw 15 or claw 20 provided with a concaved serrated gripping surface 21. The lateral edges of the claw extend beyond the sides of shank 17 and form shoulders 22 which abut against the edges of the side walls of 20 the handle at their outer ends, when the shank is in retracted position.

At its inner end the shank is provided with a central longitudinally extending bore 23 in which a coiled spring 24 is disposed. 25 This spring at one end bears against one of the screws 19 with whose receptive opening 18 the bore 23 merges, and at its opposite end said spring bears against a threaded plug 25 turned into the outer end of bore 23. The spring thus bearing against the stationary screw and against the plug which is movable with the shank, exerts a tension 30 against said shank for normally maintaining the latter in retracted position within 35 the handle.

The upper surface of shank 17 adjacent the claw 20 and near ears 7, is provided with a concave bearing portion 26 for the reception of a cam 27 formed on the inner end of 40 lever 12 adjacent the pivot point 13. The terminal of bearing 26 on its upper side is defined by a lug or shoulder 28, adapted to be engaged by shoulder 29 provided on lever 12 adjacent the cam 27, when the lever is 45 moved into its ultimate outward position, whereby to limit the outward movement of said lever. When the lever is in the outwardly swung position indicated in Fig. 1, the cam 27 is not in engagement with its bearing, but projects within the cavity in a 50 loose manner. When, however, the lever is swung inwardly into the position shown in Fig. 2, the cam 27 in moving forwardly engages against the portion of the recess 26 defined by the rear surface of claw 20 whereby to move said claw outwardly against the tension of spring 24 and into engagement 55 with the work in the manner indicated. This outwardly shifting movement of the claw or jaw is attained simultaneously with the opposite binding movement of the chain in being stretched upon the work through action of the lever, so that it will be seen 60 that the tension of the chain and claw are

simultaneously moved against the work and 65 in opposite directions and by the manipulation of the lever in a single direction. When the wrench is thus clamped or locked upon the work, said wrench may be moved in either direction without danger of slipping. 70 An outward shifting movement of the lever from locking position will result in a relaxation of the tension of the chain and simultaneously with the inward shifting movement, and hence relaxation of the tension of 75 the claw or jaw, by reason of the spring control of the latter, so that a full unlocking movement of the wrench relatively to the work, is thus provided by merely shifting the lever outwardly. 80

Although I have described the preferred embodiment of my invention, I may desire to make such changes in the construction, combination and arrangement of parts thereof as do not depart from the spirit of the 85 invention and the scope of the appended claims.

I claim:—

1. A wrench comprising a substantially U-shaped handle having oppositely disposed 90 pairs of ears provided at its inner end, a shank shiftable longitudinally of said handle and disposed therein, means for limiting the shifting movement of the shank, a serrated claw provided on the shank and movable 95 into engagement with a piece of work, spring means for maintaining the claw normally in retracted position, a flexible chain pivoted at one end between one of said pair of ears, a lever pivoted at its inner end between the opposite pair of ears, a lug provided on said lever and adapted to engage said chain whereby to tighten the latter against the work when the lever is moved inwardly, a bearing provided in the shank 105 adjacent the claw, a cam provided on the lever and movable into engagement with said bearing when the lever is moved inwardly whereby to shift said claw outwardly 110 into engagement with the work, and coacting means between the lever and claw for limiting the outward movement of the former.

2. A wrench comprising a substantially U-shaped handle, a shank disposed within 115 the handle and movable longitudinally thereof, said shank being provided with a plurality of spaced elongated openings, removable elements carried by the handle and engaging through said openings, said elements adapted to limit the movements of the shank, a claw carried by said shank and movable into engagement with a piece of work when said shank is shifted outwardly, said shank at its inner end being provided 120 with a bore merging with one of the openings in the shank, a plug disposed in the outer end of the bore, a spring disposed be-

tween said plug and the retaining element extending through last said opening, said spring adapted to maintain said shank in retracted position within the handle, a flexible chain pivotally connected to the handle, a lever pivoted to said handle and provided with means for engaging said chain whereby to lock the latter upon a piece of work when the lever is moved inwardly, and co-acting

means between said lever and claw whereby 10 to shift the latter outwardly into engagement with the work simultaneously with the locking movement of the chain.

ROBERT J. COSSEBOOM.
